LUBRICATING ATTACHMENT

Max Rosenberg and Joseph Weissblatt,
New York, N. Y.

Application June 23, 1941, Serial No. 399,391

5 Claims. (Cl. 112—256)

This invention relates to a lubricating attachment for the cutting members of pinking attachments used in connection with sewing machines.

In pinking attachments having V-shaped cutting members and used at present with sewing machines, the cutting edges dull quickly necessitating frequent changing of the cutting members and causing much loss in the running time of the machine. This quick dulling of the cutting edges is caused by the rubbing of the vertical front edges of the movable cutting member against guide members extending upwardly from the female cutting member.

An object of this invention is to provide a simple compact lubricating appliance which may be removably mounted on the pinking attachment base and comprising two arms having their free end portions positioned in V-shaped form and terminating in pockets for felted fibers which are in contacting relation with the V-shaped cutting edges of the movable cutting member.

Another object of this invention is to provide a resilient means for causing a frictional pressure between the felted fibers and the V-shaped cutting edges.

Another object of this invention is to provide means for regulating the pressure between the felted fibers and the V-shaped faces of the movable cutting member.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a side elevation of a pinking attachment in operating position in a sewing machine, with the lubricating attachment applied to the cutting member.

Figure 2 is a cross-sectional view, the section being taken as on line 2—2 in Figure 1.

Figure 3 is a cross-sectional view, the section being taken as on line 3—3 in Figure 2.

Figure 4 is a plan view of the lubricating device removed from the pinking attachment, the front screws being removed to permit swinging motion of the arms.

Figure 5 is a plan view of a modified lubricating attachment, partly broken away to show the interior of one of the pockets.

In the illustrated embodiment of the invention the numeral 10 indicates a pinking attachment to which our lubricating attachment 11 has been applied.

5 The pinking attachment comprises a base 12 having upwardly extending arms 13 at one end, designed to form guide means for a cutter arm 14 mounted on a pivot 15, extending through said arms.

10 The pinking attachment 10 has a screw 16 serving to limit the upward movement of the cutter arm 14 to a predetermined maximum, as is well known in the art.

15 At the free end 17 of the cutter arm 14 there have been provided arms 18 designed to form guide means for a bar pivotally mounted on a pin 20 extending through said arms.

20 A male cutting member 21 of triangular prismatic form is fastened to the bar 19 by means of a bolt 22. A female cutting member 23 is fastened to the base 12 and is provided with a V-shaped opening 24 and with upwardly extending guide members 25, forming continuations of and having the same inclination as the sides 25 of the V-shaped opening 24. The guide members 25 are spaced away from the apex of the opening 24 and extend upwardly a distance sufficient so as to be constantly in engagement with the rear portions of the cutting walls of the male 30 cutting member 21, and serve to maintain the male and female cutting members in alignment.

25 A ribbon-like leaf spring 26 has been fastened to the cutter arm 14 and extends angularly against the bar 19 and serves to swing the cutting member 21 outwardly about the pin 20 into forced engagement with the female cutting member 23.

30 Figure 1 shows the pinking attachment 10 mounted on the base plate 30 of a sewing machine 31 and is attached thereto by means of a bolt 32 passing through an elongated aperture in the base 12 of the pinking attachment 10.

35 The cutter arm 14 has been provided at its upper portion with a bifurcated extension 33 having a pin 34. A link 35 has been pivotally mounted on the pin 34 and is connected at its upper end to the actuating mechanism of the sewing machine, as is well known in the art, shown in Patent No. 1,922,453.

40 The lubricating attachment 11 comprises a channel-shaped base 40 having an elongated slot 41 through which passes the bolt 32 and by means of which the lubricating attachment 11 is secured to the base 12 of the pinking attachment 10. The flanges 42 of the channel-shaped base

40 have been spaced apart so as to engage the upright sides of the base 12.

Arms 43 have been secured to the lubricating attachment base 40 by means of screws 44. The arms 43 are elongated and extend in the direction of the male cutting member 21. The free end portions of the arms 43 are positioned in V-shaped form and terminate in separate and independent rhomboid pockets 45 serving to receive substantially rhomboid shaped blocks 46 of felted fibers, in forced engagement.

The felted fiber blocks 46 extend outwardly from the pockets 45 sufficiently to form a V-shaped opening between them wherein the cutting walls of the male cutting member 21 are frictionally engaged.

As shown in Figure 3, the lubricating attachment 11 is slidably mounted on the base 12 with the flanges 42 in engagement with said base. It is thus possible to longitudinally adjust the lubricating attachment 11 on the base 12 to provide the desired frictional pressure engagement between the felted blocks 46 and the male cutting member 21.

It is to be noted that a presser-foot 47 extends under one of the arms 43 and that the arms are made of spring steel to permit raising one of said arms when the presser-foot is raised.

It is to be noted that while we prefer to use blocks of felted fiber, that other lubricant absorbing and storing means may be used in the pockets. Holes 48 in the upper layers of the pockets 45 are provided for periodically supplying oil to the felted fiber blocks.

Figure 5 shows a modified lubricating attachment 50 comprising a base 51 having spring arms 52, 52' mounted on shoulder screw pivots 53. The arms have radially positioned slots 54 adapted for engagement with shoulder screws (not shown) threaded into tapped holes 56.

As best shown in Figure 5, it will be seen that the junction 46' of the felted blocks 46 is of considerable linear extent or depth to provide sufficient contact between the felt blocks at the apex of the cutting member 21.

The arms terminate in independent rhomboid pockets 55 similar to the independent pockets 45 shown in Figure 4. The arm 52 has one end of a coil spring 57 secured thereto by a screw 58. The other end of the spring 57 is secured to a threaded bar 59 which passes through ears 60 integral with the arm 52'. A wing nut 61 in threaded engagement with the threaded end of the bar 59 serves for adjusting the spring arms so as to bring the felted fiber blocks 46 in frictional contacting relation with the male cutting member 21. The wing nut serves as a means for regulating the pressure between the felted fibers against the V-shaped faces of the movable cutting member.

The slots 54 are open at one end to permit swinging of the arms about the pivots 53, clear of the cutting member 21. It is to be noted that the spring 57 serves as a means for the automatic transverse adjustment of the arms 52, 52' and the felt blocks 46. It is also to be noted that the shoulder screws 53 permit free pivotal movement of the arms 52, 52' when they are drawn together by the spring 57.

In accordance with the patent statutes we have described and illustrated preferred embodiments of our invention, but it will be understood that various changes and modifications can be made therein without departing from the spirit of the invention as defined by the appended claims.

We claim:

1. In a pinking attachment having a base and V-shaped cutting members one of which is vertically reciprocable, a lubricating attachment adapted to be mounted on said base and having arms extending therefrom in the direction of said reciprocable cutting member, said arms having their free end portions positioned in V-shaped form and terminating in separate and independent pockets on opposite sides of said reciprocable cutting member, blocks of felted fiber mounted in forced engagement in said pockets and extending outwardly from said pockets sufficiently to form a V-shaped opening between them defined by two felt surfaces, the said felt surfaces contacting along a common vertical plane, and means for adjusting said lubricating attachment lengthwise of said pinking attachment base to repeatedly bring the walls of said V-shaped felted opening into engagement with the outer surfaces of said reciprocable cutting member whereby the cutting edges of said reciprocable cutting members are lubricated.

2. A lubricating device for a pinking attachment having cutting members one of which is vertically reciprocable, comprising means for mounting said lubricating device on the pinking attachment and having spring means extending therefrom in the direction of said reciprocable cutting member, said spring means having their free end portions positioned in converging angular form and terminating in pockets on opposite sides of said reciprocable cutting member, lubricant absorbing means mounted in said pockets and extending outwardly sufficiently to form a V-shaped opening between them, and means for adjusting said lubricating attachment to bring the walls of said V-shaped lubricant absorbing means into engagement with the outer surfaces of said reciprocable cutting member.

3. A lubricating device for a pinking attachment having cutting members one of which is vertically reciprocable, comprising means for mounting said lubricating device on the pinking attachment and having spring arms extending therefrom in the direction of said reciprocable cutting member, said spring arms having free end portions positioned in converging angular form and terminating in pockets on opposite sides of said reciprocable cutting member, lubricant absorbing means mounted in said pockets and extending outwardly sufficiently to form a V-shaped opening between them, and means for automatically adjusting said arms to bring the walls of said V-shaped lubricant absorbing means into frictional engagement with both cutting sides of said reciprocable cutting member.

4. A lubricating device for a pinking attachment having cutting members one of which is vertically reciprocable, comprising means for mounting said lubricating device on said pinking attachment and having spring arms extending therefrom in the direction of said reciprocable cutting member, said spring arms having free end portions positioned in converging angular form and terminating in pockets on opposite sides of said reciprocable cutting member, at least one of said arms being movable vertically at its free end, lubricant absorbing and storing means in said pockets and extending outwardly sufficiently to form a V-shaped opening between them, and means for automatically adjusting said arms to bring said V-shaped lubricant absorbing means into desired frictional engagement with the outer surface of said reciprocable cutting member.

5. A lubricating device for a pinking sewing machine having cutting members one of which is reciprocable, comprising means for mounting said lubricating device on the pinking machine and having arms extending therefrom in the direction of said reciprocable cutting member, said extending arms having free end portions positioned in converging angular form and terminating in pockets on opposite sides of said cutting member, blocks of felted fiber mounted in forced engagement in said pockets and extending outwardly from said pockets sufficiently to form a felted V-shaped opening between them defined by two felt surfaces, the said felt surfaces contacting along

10 a common vertical plane, and means for adjusting said lubricating attachment lengthwise of said pinking attachment base to bring the walls of said V-shaped felted opening into engagement with the outer surfaces of said reciprocable cutting member whereby the cutting edge of said reciprocable cutting member is lubricated, said reciprocable cutting member being contacted solely by said felt surfaces and being wholly out of contact with said arms or carriers of said blocks of felted fiber.
